UNITED STATES PATENT OFFICE.

JOHN KEARNS, OF CHICOOEE FALLS, MASSACHUSETTS.

TANK AND WASHING-DRUM.

1,160,512.

Specification of Letters Patent. Patented Nov. 16, 1915.

Application filed May 21, 1915. Serial No. 29,678.

To all whom it may concern:

Be it known that I, JOHN KEARNS, a citizen of the United States of America, residing at Chicopee Falls, in the county of 5 Hampden and State of Massachusetts, have invented certain new and useful Improvements in Tanks and Washing-Drums, of which the following is a specification.

This invention relates to tanks and washing drums.

More specifically, it relates to such apparatus as is applied in the process of reclaiming rubber from scraps of fabric or other waste material.

15 An object of the invention is to provide a simple, inexpensive apparatus wherein waste material, containing rubber, may be subjected to a thorough washing in a solvent solution.

20 Another object is to provide a structure coöperative with the above apparatus, wherein the waste material, after having been washed in the solvent solution, may be allowed to drain while another batch of 25 scraps is being washed.

Another object is to provide an improved structure of the class described, wherein the washing and draining processes may be carried on rapidly and efficiently.

30 Other objects and advantages will appear in the detailed description to follow.

In general, my apparatus comprises a tank with two compartments, a drum, the peripheral surface thereof being perforated, 35 said drum adapted to be rotated in either compartment, a door in the drum to allow material to be placed therein, and operative supporting means and driving connections for said drum. One compartment is adapted to contain a solvent solution for rubber and the drum, adapted to contain the material from which the rubber is to be reclaimed, is rotatable within this compartment. The solvent enters the drum through 40 the numerous holes in the periphery thereof and dissolves the rubber from the scrap material. The drum is so mounted that it may be swung over the second compartment to allow the scrap material, from 45 which the rubber has been dissolved, to drop through the door of the drum upon a screen. Here, the material is allowed to drain, and the solvent solution passes to the bottom of the tank.

50 A preferred embodiment of my invention

is illustrated in the accompanying drawings, in which—

Figure 1 is a side elevational view of my apparatus. Fig. 2 is a plan view thereof. Fig. 3 is an end elevational view, partly in section, of the washing drum. Figs. 4 and 5 are detail views hereinafter to be described.

Referring to the drawings, particularly to Figs. 1 and 2, 1 is a boxlike structure 65 built up, preferably, of plates and angle irons. Centrally located and vertically arranged within the structure 1 is a partition 4 of waterproof material which forms two compartments 2 and 3. The compartment 3 is provided near the lower portion thereof with a screen 17 of wire mesh or other suitable material, said screen being suitably supported by angle irons riveted to the member 1. Secured to the sides of the structure 1 and slightly below the top are angle iron shelves 22. These shelves 22 support a pair of bearings 10 centrally arranged with respect to the structure 1. Also mounted on the shelves 22 are two pairs of bearings 13 70 and 14 centrally arranged with respect to the compartments 3 and 2, respectively. Rotatably mounted within the journals 10 is a shaft 11 adapted to be driven from any suitable source of power by the pulley 5. 80 Loosely mounted and centrally pivoted upon the shaft 11 are a pair of levers or arms 6. The arms 6 at one extremity are journaled to receive the stub shafts 8 which are fixedly secured to a drum 7. The arms 6 at the other extremity are provided with weights 12 to counterbalance the weight of the drum 7. The stub shafts 8 and the drum 7 are driven from the shaft 11 by sprockets and the chain 9. The bearings 14, 90 previously described, are adapted to support the stub shafts 8, when the parts are in the position shown in Fig. 1. The bearings 13 support the shafts 8 in a similar manner when the drum 7 is in the compartment 3. 95

The drum 7, more clearly shown in Fig. 3, comprises a pair of heads 7', connected by flanges to the stub shafts 8, and a cylindrically bent plate 7², suitably connected to the heads 7' by angle irons and rivets. The entire peripheral surface of the plate 7² is perforated with small holes 16. A door 19, also perforated with holes 16, is hinged to the drum 7 at 20. The lower edge of the door 110

19 is provided with slots 22' (see Figs. 4 and 5) and located within the slots 22' are the T-shaped handles 21. The latter are rotatably mounted in the plate 7² and are adapted, when in the position shown in full lines in Fig. 5 to keep the door 19 closed. When, however, the handles 21 are given a quarter turn, the projecting arms thereof register with the slot 22' and the door may be opened as indicated by dotted lines in Figs. 4 and 5.

In operation, scraps of fabric containing rubber to be reclaimed are placed within the drum 7 and the door 19 is closed and locked. The compartment 2 is filled with a solvent solution for rubber, and the drum 7 is rotated therein by the driving connections described. The solvent enters through the numerous holes 16, and the constant rotation of the drum shakes up the scraps of fabric and subjects them to a thorough washing. After this operation has continued a sufficient length of time to dissolve all of the rubber from the fabric scraps, the power is stopped, and the lever arms 6 are rotated through an arc of 180 degrees bringing the drum over the compartment 3. The door 19 is then opened, and the scraps within the drum are allowed to fall upon the screen 17. Here they are allowed to drain, the liquid passing to the bottom 18 of the compartment from whence it may be drawn off by any suitable means.

What I claim is—

1. A tank and washing drum, comprising, in combination, a tank divided into two compartments, a drum, the peripheral surface thereof being perforated, means to rotate said drum, and means to support said drum over and partially within either compartment, as desired.
2. A tank and washing drum, comprising, in combination, a tank divided into two compartments, a drum, the peripheral surface

thereof being perforated, a door in said drum, means to hold said door in a closed position, means to rotate said drum, and means to support said drum over and partially within either compartment.

3. A tank and washing drum, comprising, in combination, a tank divided into two compartments, a drum, the peripheral surface thereof being perforated, a door in said drum, means to hold said door in a closed position, levers centrally and pivotally mounted on said tank, said levers adapted to support said drum over either compartment as desired, and means to rotate said drum.

4. A tank and washing drum, comprising, in combination, a tank divided into two compartments, counterweighted arms pivotally mounted on said tank, a drum the peripheral surface thereof being perforated, said drum being rotatably mounted in and supported by said arms, said arms adapted to support said drum over and partially within either compartment as desired, a door in the peripheral surface of said drum, means to lock said door to said drum, and means to rotate said drum in either compartment, as desired.

5. A tank and washing drum, comprising, in combination, a tank divided into two compartments, a screen in one of said compartments, counterweighted arms centrally and pivotally mounted on said tank, a drum the peripheral surface thereof being perforated, said drum adapted to be rotatably supported by said arms, said arms adapted to support said drum over and partially within either compartment as desired, a door in the peripheral surface of said drum, means to lock said door to said drum, driving means to rotate said drum in either compartment as desired, and means to swing said arms on their pivotal supports without disturbing said driving means.

JOHN KEARNS.
